UNITED STATES PATENT OFFICE.

FREDRICK C. CUCKSON, OF MALONE, NEW YORK.

SAFETY-ENVELOP.

SPECIFICATION forming part of Letters Patent No. 608,583, dated August 9, 1898.

Application filed November 19, 1897. Serial No. 659,108. (No model.)

To all whom it may concern:

Be it known that I, FREDRICK C. CUCKSON, a citizen of the United States, residing at Malone, in the county of Franklin and State 5 of New York, have invented a new and useful Improvement in Safety-Envelops, of which the following is a full, clear, and exact specification.

My invention relates to a new and useful 10 improvement in safety-envelops, and has for its object to provide an exceedingly simple and effective device of this description which will effectually prevent the unlawful tampering with the letter without easy detection 15 thereof.

With this end in view this invention consists in the details of construction and combination of elements hereinafter set forth, and then specifically designated by the claim.

20 In order that those skilled in the art to which this invention appertains may understand how to make and use the same, the construction and operation will now be described in detail, referring to the accompanying 25 drawings, forming a part of this specification, in which—

Figure 1 is a rear view of an envelop made in accordance with my improvement, the closing-flap being shown in an open position, 30 while the gummed tongue of the lower flap is shown in dotted lines as being passed through the slits formed in the side flaps; Fig. 2, a similar view showing both the upper and lower flaps opened; Fig. 3, a central cross-section of Fig. 1; Fig. 4, a similar view showing the closing-flap in its closed position, and Fig. 5 a perspective illustrating the methods of sealing the envelop by passing the safety-tongue of the closing-flap through the slits in 40 the side flaps.

In carrying out my invention as here embodied I cut the envelop-blank in the usual manner, forming the body A, end flaps B, lower flap C, and upper or closing flap D, the 45 two latter flaps having tongues E and F formed therewith. In the formation of the blank, slits G are formed therein, as clearly shown in Fig. 2, so that when these two flaps are folded in position these slits register with 50 each other and are for the passage of the

tongues E and F, as will be hereinafter set forth.

The tongue E is gummed upon its upper surface and is folded upon the line H, so that when the envelop is to be closed this tongue 55 is passed through the slits G and carried downward, as shown in dotted lines in Fig. 1 and in full lines in Figs. 3 and 4. After this has been accomplished the outer surface of the tongue F is moistened and also passed 60 through the slits G, so as to lie beneath the tongue E, and the moisture thereon will cause it to adhere to the last-named tongue, thereby securely sealing the envelop and avoiding the possibility of the same being opened with- 65 out affording means for easy detection by the most casual observer.

It is obvious that an envelop thus made and sealed precludes the possibility of access being had to the adhesive surfaces, since 70 these are upon the inside of the envelop and therefore cannot be acted upon to cause their disengagement.

If desired, when the envelop is manufactured the lower flap may be sealed along the 75 edges I and the tongue E passed through the slits G, so that when using the envelop it will only be necessary to place the letter therein through the upper flap, moisten the outer surface of the tongue F, and pass it through 80 the slits G to seal the letter.

One of the principal advantages of my improvement is the fact that the cost of manufacture is not increased over the ordinary envelop, while absolute safety is had against 85 unauthorized tampering with the letter without plainly showing that such has been attempted.

Of course I do not wish to be limited to the exact design here shown, as my improvement 90 may be utilized in connection with any size or style of envelop.

Having thus fully described my invention, what I claim as new and useful is—

A safety-envelop consisting of a body, two 95 end flaps having slits therein adapted to register when folded, a bottom flap having a tongue formed therewith adapted to pass through said slits and turn backward and downward upon itself, gum being applied to 100

the outer surface thereof prior to its insertion through said slits, and a closing-flap also having a tongue formed therewith adapted to pass through said slits and beneath the first-named tongue, so that when moistened prior to its insertion will cause an adhesion between the two tongues, as and for the purpose set forth.

In testimony whereof I have hereunto affixed my signature in the presence of two subscribing witnesses.

FRED. C. CUCKSON.
